UNITED STATES PATENT OFFICE.

FREDERICK M. VENZIE, OF PHILADELPHIA, PENNSYLVANIA.

BUILDING CONSTRUCTION.

Application filed July 14, 1923. Serial No. 651,491.

This invention, generally stated, relates to building construction and has more particular relation to the manner of forming ceilings, walls, partitions and the like, of 5 plaster-board and equivalent material.

The leading object of the present invention is to provide a simple, efficient and comparatively inexpensive way of forming a ceiling, wall, partition and the like of plaster-board, slabs or equivalent material, without employing metal-lath or the like, as now commonly practiced, for supporting the plastering material. A further object resides in the provision of specially formed 10 slabs and clips for accomplishing the results sought by said leading object.

A further object is to provide an arch-form shaped to prevent lateral movement of the clips employed.

20 The invention consists of the improvements hereinafter described and finally claimed.

The nature, characteristic features and scope of the invention will be more fully 25 understood from the following description, taken in connection with the accompanying drawings forming part hereof and in which:—

Fig. 1, is a fragmentary view, in section, 30 of a ceiling formed in accordance with the present invention.

Fig. 2, is a top or plan view thereof,

Fig. 3, is a plan view of one of the slabs,

Fig. 4, is a side view of one of the clips,

35 and

Fig. 5, is a side view of an arch-support.

For illustrative purposes I have shown in the drawings an embodiment of the present invention as applied to ceilings and the following description is restricted thereto, although obviously the invention is applicable to walls, partitions and the like, and further, general details of construction and arrangement of parts may be varied without departing 40 from the spirit or scope of the present invention.

In the drawings 10, designates a slab of suitable material. This may be plaster-board or a cork, saw-dust or equivalent composition, the ingredients of which form no 50 part of the present invention. The edges of said slab are beveled as at 12, for a purpose to presently appear. Opposite sides of the slab 10, are provided with a plurality of 55 slots 13, usually in the form of saw-kerfs as this forms a ready and inexpensive manner

of formation. These slots are to accommodate spring clips about to be described. The clips are of metal, formed in one piece and each comprises a substantially looped part 60 14 the ends of which are extended inwardly in parallelism, as at 15—15, to provide legs and then are extended outwardly with respect to parts 15—15 to provide opposed feet 16. The manner of using such slabs and 65 clips will now be described. 17 designate I-beams as are used in ceiling construction and between adjacent I-beams are horizontally arranged my slabs and clips. Temporary supports or frames 18 are employed as usual in this class of work. Upon these supports and between the I-beams I position my slabs 10 as shown in Fig. 1. I next position upon each slab 10 an arch-form 19 opposed sides of which 70 are flanged at 20. Each flange is slotted in register with the slots 13 of a slab 10. Each slotted portion of a flange 20 is provided with a lip 22 capable of being bent from the position shown in Fig. 5, to that 80 shown in Fig. 2, in order to provide a guard as hereinafter described. With the arch-forms superimposed upon the slabs I next fit to the registering slots of the arch-forms and slabs the clips above described. In the 85 connection it is to be noted that the lips 22 of the arch-forms are in open position as shown in Fig. 5. The parts 15—15 of the clips are accommodated in said slotted parts with the feet 16 beneath the slabs and the 90 looped parts 14 projected above the arch-forms as clearly shown in Fig. 1. Each loop part acts as a spring to normally spread apart a pair of legs 15. The lips 22 are then 95 bent downwardly to close the open ends of the slots of the arch-forms thus preventing lateral or side-wise movement of the clips. This is important while the mechanics are at work and before plaster is applied.

A fill of plaster or the like 23 is then applied between the I-beams, upon the arch-forms and between the bevels of the slabs. Air spaces 24 are thus left between the slab tops and the arch-forms. Conventional reinforcing rods are usually employed. 100 When the material 23 has set the temporary supports are removed and a thin finishing coat of plaster applied to the under surface of the slabs as indicated at 26 at the right hand side of Fig. 1. Since a slab is in effect a 110 rough-coat of plaster but a very thin coat of finishing plaster is necessary. In the

event that it becomes necessary to cut away a portion of a slab for any reason, as in installing light fixtures for instance, said clips serve to maintain the remaining portion of the slab in position. The clips also function to preclude sidewise movement of the arch-forms.

The beveled parts of adjacent slabs serve as a good anchorage for the plaster or like material 23.

What I claim is:—

1. In combination, I-beams, slabs the opposed sides of which are slotted, positioned between said I-beams, an arch-form 15 mounted upon each slab and having flanged parts slotted in register with said slab slots, clips having looped tops and parallel leg portions terminating in opposed feet fitted within said registering slots with the feet 20 arranged beneath the slabs and the looped tops above said arch-forms and a plaster or like fill between said beams and upon said arch-forms, there being thus left an air space between a slab and an arch-form.
2. In combination, I-beams, slabs the opposed sides of which are slotted, positioned between said I-beams, an arch-form mounted upon each slab and having flanged parts slotted in register with said slab slots, each 30 slotted portion of said arch-form being provided with a lip for closing a slot opening to prevent lateral movement of a clip, clips having looped tops and parallel leg portions terminating in opposed feet fitted within 35 said registering slots with the feet arranged beneath the slabs and the looped tops above said arch-forms and a plaster or like fill between said beams and upon said arch-forms, there being thus left an air space 40 between a slab and an arch-form.
3. In combination, I-beams, slabs the opposed sides of which are slotted, positioned between said I-beams, an arch-form mounted upon each slab and having flanged parts 45 slotted in register with said slab slots, clips having looped tops and parallel leg portions terminating in opposed feet fitted within said registering slots with the feet arranged beneath the slabs and the looped tops above 50 said arch-forms, a plaster or like fill between said beams and upon said arch-forms, there being thus left an air space between a slab and an arch-form, and a thin finishing coat of plaster for the exposed face of the slabs.
4. In combination, I-beams, slabs the op-

posed sides of which are slotted, positioned between said I-beams, said slabs having beveled edges, an arch-form mounted upon each slab and having flanged parts slotted in register with said slab slots, clips having looped tops and parallel leg portions terminating in opposed feet fitted within said registering slots with the feet arranged beneath the slabs and the looped tops above said arch-forms and a plaster or like fill between 65 said beams and upon said arch-forms, there being thus left an air space between a slab and an arch-form.

5. In combination, spaced beams or girders, slabs the opposed sides of which are 70 slotted, arranged between said beams or girders, an arch-form mounted upon each slab having slotted parts in register with the slab slots, bowed clips having feet engaging said registering slots, means to retain the 75 slips against lateral movement, a plaster or like fill between said beams or girders and upon said arch-forms, there being left an air space between each slab and arch-form.

6. A structure of the character stated comprising spaced beams, a slab arranged between said beams the opposed sides of which slab are slotted, an arch-form mounted upon said slab having slotted parts in register with the slab slots, and spring clips having 80 normally spread legs, said legs engaging said slotted parts.

7. A structure of the character stated comprising spaced beams, a slab arranged between said beams the opposed sides of which 90 slab are slotted, an arch-form mounted upon said slab having slotted parts in register with the slab slots, spring clips having normally spread legs, said legs engaging said slotted parts, and means to retain said 95 clips against lateral movement.

8. A structure of the character stated comprising spaced beams, a slab arranged between said beams the opposed sides of which slab are slotted, an arch-form mounted upon 100 said slab having slotted parts in register with the slab slots, spring clips having normally spread legs, said legs engaging said slotted parts, means to retain said clips against lateral movement, and a cementitious 105 fill between said beams and covering said forms.

In testimony whereof I have hereunto signed my name.

FREDERICK M. VENZIE.
